UNITED STATES PATENT OFFICE

123,204

DESIGN FOR A BOTTLE

Leonard Carey, Covington, Ky.

Application May 14, 1940, Serial No. 92,367

Term of patent 14 years

To all whom it may concern:

Be it known that I, Leonard Carey, a citizen of the United States, residing at 227 Riverside Drive, Covington, in the county of Kenton and State of Kentucky, have invented a new, original, and ornamental Design for Bottles, of which the following is a specification, reference being had to the accompanying drawing, forming a part thereof.

I claim:

The ornamental design for a bottle, as shown.

LEONARD CAREY.
